UNITED STATES PATENT OFFICE.

THELMA M. REYNOLDS, OF ST. PAUL, MINNESOTA.

PERMANENT WAVER.

Application filed March 12, 1927. Serial No. 174,766.

The present invention relates to a hair curler and more particularly to a hair curler of the type intended to produce a permanent wave in the hair.

5 The most desirable type of natural wave in the hair is a comparatively large, soft wave, without any suggestion of kinkiness, since this type of wave is adapted to the production of coiffures which accentuate the natural beauty of the face.

It is contemplated in the present instance to wave hair by coiling the hair in the form of a substantially flat helix upon a device which retains hair in said form, and applying heat to the hair while thus retained in position to produce a wave therein.

10 In order to accomplish this object, there is provided, in accordance with one feature of the invention, a spool or bobbin having a flange on either end thereof, and a casing adapted to receive said spool or bobbin, said casing having electrical heating elements therein to heat hair wound upon said spool.

These and other features of the invention 15 will be more fully brought out in the following description and the accompanying drawings, wherein:

Figure 1, is a view in section through the separated component parts of a spool upon 20 which a coil of hair may be formed.

Figure 2, is a longitudinal section through a casing for holding said spool.

Figure 3, is a view in section similar to that shown in Figure 2, showing the spool 25 of Figure 1 assembled and in position within said casing.

Figure 4, is a transverse sectional view through the spool with a coil of hair wound thereon; and

40 Figure 5, is a view in lower elevation of the structure illustrated in Figure 2.

Referring to the drawings in detail, Figure 1 shows the component parts of a spool used for winding hair into a flat helical coil for 45 waving, the spool being comprised of a base portion A having an internally threaded tubular shank 1 and an annular flange 2 extending outwardly from the lower end of the shank portion. A pair of circular washers 50 3 and 4 of absorbent material are of the same outside diameter as the flange 2 and are each provided with a central opening 5 of a size to slip over the shank 1. A second flanged element B has a flange 6 thereon the same size as the flange 2 of the base member and is provided with a central open-

ing 7 therein of a size to freely slip over the shank 1 of the base member A. A cap member C is provided with a tubular central portion 9 having external threads thereon of a size to threadedly engage the internally threaded portion of the base member A and is provided with an encircling skirt portion 10 spaced outwardly from the central portion 9 thereof to rest upon the flanged element B 60 to force it into closer relation to the flange 2 of the base member A when screwed into position upon said base member. A heating casing D is provided having a cup-shaped receptacle 11 with a heating element 12 retained in position in the closed end thereof by means of a transverse plate 13. The heating element 12 is connected by conductors encased within a cord 14 to a suitable source of electrical current. The cup-shaped casing 11 has a slot 15 in the side thereof of a size to receive a trough-shaped portion 16 extending outwardly from a closure member E which is slidably insertable within the cup-shaped casing D, as best illustrated in 70 Figure 3. The closure member E comprises a shallow receptacle 17 in which a second heating element 18 is mounted connected to conductors enclosed in a cord 19 similar to that described for the element 12. A plate 75 20 covers the heating element 18 and is permanently united to the sides of the shallow member 17 as by crimping. A central post 21 is mounted upon the plate 20, said post being of a size to be freely insertable within 80 the central aperture of the hair containing spool, when assembled. This central post transmits heat upwardly from the heating element by direct conduction which assists in heating the spool and hair wound thereon 85 uniformly throughout.

A sliding ring 22 encircles the casing D to have a close sliding fit thereon, and is retained in position thereon by means of beads 100 23 and 24 near the upper and lower edges, respectively, of said casing. A trough-shaped extension 25 is provided upon one side of the ring 22 to register with the trough-shaped extension 16 of the closure member E to grip the hair which projects from the casing when the device is in position for operation and to aid in preventing the escape of steam from the interior of the device. Knobs 26 and 27 are provided upon the casing D and upon the closure member E, respectively, for manipulating the device and are preferably of a substance which is a poor 105 110

conductor of heat so as to permit manipulating the device when the parts are heated by the operation of the heating elements.

In using the device the absorbent washers 3 and 4 are moistened with a suitable solution, such as borax water. One of the washers 3 is placed in position over the tubular shank 1 of the base member A of the spool to lie closely against the flange 2 of the base member, while the other absorbent washer 4 is positioned to lie closely against the flange 6 of the member B which is then slipped upon the shank 1. The cap member C is then screwed in position to retain the member B 15 in position upon the shank 1.

A lock 30 of hair is then separated from the remainder of the hair upon the head of the person to be treated and is wound upon the spool in the form of a substantially flat 20 helix, as shown in Figure 4. The cap C may then be screwed down to grip the coil of hair, by forcing the member B toward the flange 2 of the base member. A strip 28 of felt, or other absorbent material, is also moistened 25 with a solution similar to that used for the washers 3 and 4 and is wrapped around the coil of hair as shown in Figure 4. The spool containing the coil of hair is then placed in position over the stud 21 of the closure member E so that the hair as it emerges from the spool will lie upon the trough-shaped extension 16. The casing D is then slipped over 30 the closure member E so that the hair as it emerges will lie within the slot 15 in the side 35 of said casing. The closure member is forced upwardly within the casing, as far as it will go, as shown in Figure 3, and the slideable ring 22 is slidably moved downward, by means of the encircling flange 29 thereof, 40 which serves as a means to manipulate said ring, so that the trough-shaped extension 25 thereof will lie closely against the emerging hair to grip the hair between this trough-shaped extension and the trough-shaped extension 16 on the member E. The parts are 45 shown in this position in Figure 3, the coil of hair, however, having been eliminated for the purpose of clarifying the drawing. Electrical energy is then supplied to the heating elements 50 to bring the enclosed parts to a required temperature, which may be readily accomplished by one conversant with the art, and the hair is left in a heated condition within the device for a required interval to 55 bake the hair so that upon removal from the device the hair will retain the wave produced by the process. Upon completion of the baking process the parts may be separated and the hair removed from the spool. 60 While the spool is here shown as having operative threaded means to hold the parts in position, it is not desired to limit the invention to this construction, since it would be 65 but the work of a mechanic of ordinary ability to change the arrangement and construc-

tion of the parts to retain the parts in position by means of friction or other similar expedients, and it is, therefore, intended to protect the invention with respect to such equivalents as defined in the appended claims.

Several of the devices are intended to be used simultaneously and, owing to their lightness and small size, it is usually possible to treat an entire head of hair at one operation. By providing extra sets of spools, other heads of hair may be prepared for the process while one is being treated.

I claim:

1. A hair curler of the character described, comprising a spool having flanges adjustably spaced apart, means to laterally compress a flat helical coil of hair wound thereon and a casing associated with said spool and having heating means carried thereby.

2. A hair curler of the character described, comprising means for holding a flat coil of hair, means associated therewith to laterally compress said coil, and heating means associated therewith to heat said laterally compressed coil of hair.

3. A hair curler of the character described, comprising a double flanged member, means controlling the spacing apart of the flanges thereof, a casing shaped to receive said double flanged member, and heating means associated with said casing to heat the contents thereof.

4. A hair curler of the character described, comprising a double flanged member, means controlling the spacing apart of the flanges thereof, a casing shaped to enclose hair wound upon said flanged member, and heating means associated with said device to heat said hair wound upon said flanged member.

5. A hair curler of the character described, comprising holding means laterally compressing a flat helical coil of hair, closure means associated therewith to enclose the laterally compressed coil of hair, and heating means operatively associated with said device to heat the coil of hair so held.

6. A hair curler of the character described, comprising a double flanged member, the flanges thereof being adjustably spaced apart, means holding the flanges thereof in varying degrees of compression toward each other, a casing to receive the flanged member therein, and heating means associated with said device to heat the hair contained therein.

7. A hair curler of the character described, comprising a hollow cored double flanged member, said flanges being adjustably spaced apart, a casing shaped to enclose said flanged member, a portion of said casing being shaped to enter the hollow core of said flanged member, and heating means associated with said device to heat hair wound upon said flanged member.

8. The method of permanently waving hair, which comprises coiling the hair in the

form of a flat helix, holding the coil of hair in lateral compression in said flat helical form, enclosing the hair while so compressed, and heating it while so compressed and enclosed.

associated therewith to control the degree of lateral compression on said coil of hair, and ¹⁰ heating means associated with said holding means to heat said coil of hair while held in lateral compression in said holding means.

In testimony whereof I affix my signature.

THELMA M. REYNOLDS.

9. A hair curler of the character described comprising means for holding a coil of hair in lateral compression, adjustable means as-
